CLAIM

The ornamental design for a facade support, as shown and described.

DESCRIPTION

FIG. 1 is a perspective of a facade support according to one embodiment of the present design with brackets used to hang the facade support on a structure shown in broken lines;

FIG. 2 is a front view thereof;

FIG. 3 is a rear view thereof;

FIG. 4 is a top view thereof;

FIG. 5 is a bottom view thereof;

FIG. 6 is a left side view of the facade support; the right side view being a mirror image thereof;

FIG. 7 is a perspective of a facade support according to another embodiment of the present design with a bracket used to hang the facade support on a structure shown in broken lines;

FIG. 8 is a front view thereof;

FIG. 9 is a rear view thereof;

FIG. 10 is a top view thereof; and,

FIG. 11 is a bottom view thereof, the left and right side views forming no part of this embodiment.

The broken lines in the drawings illustrate portions of the facade support which form no part of the claimed design. The facade support FIGS. 7-11 are shown with a symbolic break in its length. The appearance of any portion of the article between the break lines forms no part of the claimed design.
